SOUND TRANSLATING APPARATUS

Frank Massa, Audubon, N. J., assignor to Radio Corporation of America, a corporation of Delaware

Application January 31, 1940, Serial No. 316,631

13 Claims. (Cl. 181—0.5)

This invention relates to sound translating apparatus, and more particularly to microphones of the type having a high degree of directivity whereby high sensitivity is obtained over a relatively small solid angle and great attenuation to received sound occurs outside of this small angle of pickup, the present invention being an improvement upon the type of microphone disclosed in the patent to Swickard, 2,085,130.

Microphones of this type, while being highly 10 directive, have the disadvantage of possessing a directional characteristic which varies greatly with frequency, and the primary object of my present invention is to provide an improved microphone of the type described which will be 15 free from the aforementioned defect.

More particularly, it is an object of my present invention to provide an improved directional microphone of the type set forth above in which the directional characteristic is substantially uniform for all frequencies.

Another object of my present invention is to provide an improved highly directional microphone as aforesaid which is compact in construction, easily portable, and highly efficient in 25 use.

In accordance with one form of my invention, I provide a plurality of groups of tubes of progressively varying length, each group constituting an individual or discrete microphone section; each covering a particular band of frequencies; and each microphone section having the same ratio between its effective or active length and the average wave length of the sound to which it responds, thereby giving a constant directional pattern for its frequency band. The output from each microphone section passes through an acoustical filter which passes only those frequencies which the particular section is designed to reproduce. After filtering, each group or section feeds a suitable transducer for converting the acoustical energy into electrical energy, and the electrical outputs are then added and represent the total microphone output. The transducer may be common to all microphone sections or a separate transducer may be employed for each section, as desired.

According to another form of my present invention, the several microphone groups are arranged in concentric circles in association with a common circular diaphragm. Preferably, the high frequency group or section feeds through a suitable acoustical filter to the central portion of the diaphragm; the next frequency band may surround the central group of pipes and feed 55

into an acoustical filter arranged in the form of a hollow, annular tube which is finally terminated on an annular section of the diaphragm surrounding the central portion thereof; a third group of pipes feeds through another hollow, annular tube constituting a third acoustical filter and surrounding the first-mentioned annulus, and so on. The particular advantages of this arrangement are that (1) extreme compactness is obtained, and (2) only a single microphone diaphragm is required.

In still another form of my invention, I provide a series of progressively longer pipes or tubes in association with a single diaphragm, the pipes being subdivided into several groups each of which groups is arranged symmetrically with respect to the geometric center of the diaphragm, and each group of pipes containing an acoustical filter which makes all the pipes of any one group attenuate predetermined frequency bands at substantially the same cut-off frequency. The effectively operating length of the line is determined by the length difference between the longest pipe and the shortest active pipe at any frequency. At the lowest frequency of operation, all of the acoustic filters pass the sound and the effective microphone length is a maximum. As the frequency increases, the filters of either the shortest group or the longest of pipes serve to cut off 30 these pipes; then the filters of the group of pipes of the next succeeding size cut off these pipes, etc., thereby making the effective microphone length decrease with increasing frequency. The effect of this is to keep the ratio of microphone 35 length to the wave length of the sound picked up by the microphone approximately constant, thus obtaining approximately constant directional characteristics at all frequencies.

The novel features that I consider characteristic of my invention are set forth with particularity in the appended claims. The invention itself, however, both as to its organization and method of operation, as well as additional objects and advantages thereof, will best be understood from the following description of several embodiments thereof, when read in connection with the accompanying drawings, in which—

Figure 1 is a central sectional view of one form of microphone according to my invention.

Figure 2 is an end view of a somewhat different form of my present invention.

Figure 3 is a wiring diagram of the electrical analogue of the microphone shown in Fig. 1.

Figure 4 is a developed view of still another form of my invention.

Figure 5 is an end view of the form of my invention shown in Fig. 4 and showing the arrangement of the pipes therein with respect to the diaphragm, and

Figure 6 is a wiring diagram of the electrical analogue of the microphone shown in Figs. 4 and 5.

Referring more particularly to the drawings, wherein similar reference characters designate corresponding parts throughout, I have shown, in Fig. 1, a casing or shell 1 enclosing a rather large volume for a purpose presently to be set forth and housing a diaphragm 3 which constitutes the vibrating element of an electro-dynamic or other suitable transducer adapted to transform acoustical energy into electrical energy. The casing 1 is provided with a pair of openings 5 and 6 to the former of which is connected a bundle or group of open-ended tubes 9 and to the latter of which is connected a second bundle or group of tubes 11, the tubes 9 and 11 constituting discrete pickup units or devices. The bundle of tubes 9 has a relatively long effective line length, that is, the length difference between the longest and shortest tubes of this group is relatively long, thereby making this group of tubes particularly responsive to the lower frequencies. On the other hand, the length of the line of the bundle of tubes 11, that is, the length difference between the longest and shortest tubes of this group, is comparatively short, so that this section of the microphone is particularly responsive to the higher frequencies.

Interposed between the diaphragm 3 and the low frequency line or section 9 is a low pass acoustic filter 13 which may comprise a cylindrical tube having a disc or partition 15 therein which divides the cylinder off into a pair of chambers 17 and 19, the disc 15 being provided with an opening 21. This arrangement provides a filter system shown in the upper half of the wiring diagram of Fig. 3 wherein Z_L corresponds to the impedance looking into the low frequency bundle of tubes 9, M_1 is the inertance of the mass of air in the opening 21, C_1 is the acoustical capacitance of the air in the chamber 17, C_2 is the acoustical capacitance of the air in the chamber 19, and Z_0 is the impedance of the diaphragm 3. The magnitudes of M_1 , C_1 , and C_2 depend on the magnitude of Z_L and Z_0 and on the cut-off frequency required.

The high frequency bundle of tubes 11 terminates into a high pass filter leading to the microphone diaphragm 3 and comprising a cylindrical member 23 in which the air column has a capacitance C_3 . The cylinder 23 is provided with a pair of openings 25 and 27 in one side thereof, the masses of air in these openings having, respectively, inertances M_2 and M_3 . If Z_H is the impedance looking into the bundle of tubes 11 and p is the pressure of the sound waves arriving at the pickup ends of the tubes 9 and 11, the complete arrangement has the relation shown in the wiring diagram of Fig. 3.

It is primarily to avoid the possibility of outside sound entering the openings 25 and 27 that the outer shell or casing 1 is provided to form a complete enclosure around the openings 25 and 27. The volume of air enclosed by the shell 1 must be large enough so that its acoustic impedance is preferably low compared to the impedances of the openings 25 and 27 at the lowest frequency at which the microphone must operate. Actually, the inertances M_2 and M_3 may be made to resonate with the volume of air in the shell 1

at the low frequency end of the microphone range, the effect being a sharp cut-off. Below this resonant cut-off frequency, however, the microphone should preferably be electrically or mechanically attenuated in response because the high pass filter will become ineffective to prevent these lower frequencies from reaching the diaphragm 3.

In Fig. 2, I have shown another form of my invention similar to that of Fig. 1 and also containing two discrete sets or groups of tubes 9 and 11. However, instead of bundling each group of tubes together as in Fig. 1, the tubes 9 may be arranged in an outer row or circle which terminates into an annular enclosure in which is mounted a partition having one or more openings corresponding to the opening 21 and providing the inertance M_1 . Similarly, the group of tubes 11 may be arranged concentrically within the group of tubes 9 and terminate into a common pipe in the side of which holes may be drilled to provide the inertances M_2 and M_3 . The electrical analogue of this arrangement is also represented by the wiring diagram shown in Fig. 3.

Although I have thus far shown and described a simple two-section microphone, that is to say, a microphone in which the acoustical vibrations have been divided into low and high bands, it is obvious that any number of sections may be employed between the lowest and highest frequency sections. In a microphone employing more than two discrete sections, the sections allotted to the intermediate frequency bands would preferably terminate into band pass filters each one of which would allow only those frequencies to pass for which the particular microphone section is intended.

A particularly useful form of my invention is shown in Figs. 4 and 5. In this form of my invention, there are coupled to the diaphragm 3 a plurality of groups of pipes 31a, 31b, 31c; 33a, 33b, 33c; 35a, 35b, 35c;—Nc. Within the tubes 31a, 31b, and 31c are placed discs 32, each having one or more openings 34 in which the mass of air has an inertance M_{31} . Between the discs 32 and the diaphragm 3 are the chambers 36, the air volume in each of which has a capacitance C_{31} . The tubes 33a, 33b, and 33c are provided with discs 38 formed with apertures 40 in which the mass of air has an inertance M_{33} , while the air volume in the chambers 42 between the discs 40 and the diaphragm 3 have acoustic capacitances C_{33} . Similarly, each of the tubes 35a, 35b, and 35c is provided with a disc 44 each of which is formed with an opening 46 in which the mass of air has an inertance M_{35} , the air volume in the chambers 48 associated therewith having acoustic capacitances C_{35} . Each group of tubes is similarly constructed and the longest tube Nc of the longest group has a partition 50 therein formed with an opening 52 in which the mass of air has an inertance M_N with the air volume in the chamber 54 between the disc 50 and the diaphragm 3 having an acoustic capacitance C_N . If the impedances looking into the set of tubes 31a, 31b, and 31c are respectively Z_{31a} , Z_{31b} , and Z_{31c} , the impedances looking into tubes 33a, 33b, and 33c are Z_{33a} , Z_{33b} , and Z_{33c} , etc., and the impedance of the diaphragm 3 is Z_0 , the electrical analogue will be as shown in Fig. 6.

The length of the line of this microphone is determined by the length difference between the length of the pipe Nc and the length of shortest pipe of the shortest effectively operating group or set of pipes at any instant. The operation of this form of microphone is as follows: At the

lowest frequency of operation, all of the acoustic filters M_{31} , C_{31} to M_n , C_n pass the sound, and the effective microphone length is a maximum. As the frequency increases, the filters M_{31} , C_{31} first cut off the pipes 31_a , 31_b , and 31_c and the effective length of the line will be the length difference between the pipe 33_a and the pipe N_c . Next, upon further increase in frequency, the filters M_{33} , C_{33} cut off the pipes 33_a , 33_b , 33_c , etc. The effective microphone length is then determined by the length difference between the pipe 35_a and the pipe N_c . In this way, the effective microphone length decreases with increasing frequency and the effect of this is to keep the ratio of microphone length to the wave length of sound approximately constant, thereby obtaining approximately constant directional characteristics at all frequencies.

Since the various groups of pipes are cut off progressively, it is apparent that the longest group of pipes is always operative and that the progressively shorter groups of pipes become progressively operative with decreasing frequency, with the relatively longer pipes tending constantly to be common to the effective or operating portion of the microphone. Of course, it is apparent that the longest tubes could be cut off first, leaving the shortest tubes to remain common to the entire working portion of the microphone without departing from the previously described mode of operation. The pipes 31_a , 31_b , and 31_c are preferably terminated by the same filter constants, as clearly shown in Fig. 6, in order to cut them off substantially simultaneously at the same frequency. The same is true with the pipes 33_a , 33_b , and 33_c , and so on. The reason for this is that I prefer to keep the active pipes symmetrically arranged over the diaphragm 3 so that no unbalanced force exists at any particular frequency which would tend to rock the diaphragm and create distortion. For this reason, also, I dispose each group of pipes symmetrically about the geometric center or axis of the diaphragm 3, as clearly shown in Fig. 5. Since, in the particular embodiment of my invention illustrated in Figs. 4 and 5, each group of tubes is arranged in groups of three, I place each tubular unit of each group 120° from the others of the same group and place the progressively longer tubes near the center of the diaphragm.

In the last-described form of my invention, it will be noted that, as the frequency increases, fewer and fewer pipes will supply sound energy to the microphone diaphragm 3, thus reducing the total actuating force driving the microphone. For the conventional pressure actuated microphone, therefore, the output will decrease with rising frequency. A special type of microphone may be used so that the microphone output will not decrease at the higher frequency, such as, for example, a condenser of crystal microphone feeding a resistance approximately equal in magnitude to the microphone impedance in the highest frequency of reproduction. Another alternative which may be used is a stiffness-controlled dynamic microphone in which the normal pressure sensitivity would increase with increasing frequency.

Although I have shown and described several embodiments of my invention, I am fully aware that many other modifications thereof, as well as changes in the particular embodiments herefore described, are possible. For example, in place of single tubes, such as the tubes 31_a , 31_b ,

and 31_c , etc., each individual tube may be replaced by a bundle or group of tubes, such as the bundles 9 and 11 of the modification shown in Fig. 1, with an appropriate acoustic filter terminating each bundle. Various other changes will, no doubt, readily suggest themselves to those skilled in the art. I, therefore, desire that my invention shall not be limited except insofar as is made necessary by the prior art and by the spirit of the appended claims.

I claim as my invention:

1. In a sound translating device, the combination of means for translating acoustical energy into electrical energy, said means including a vibratile element, and a plurality of groups of pickup devices of the line type coupled to said element and adapted to direct acoustical energy thereto, each of said groups of devices having a different line length than any other of said groups whereby to be effective over a different predetermined frequency range to transmit energy to said element.

2. In a sound translating device, the combination of means for translating acoustical energy into electrical energy, said means including a vibratile element, and a plurality of groups of pickup devices of the line type coupled to said element and adapted to direct acoustical energy thereto, said groups of devices each having a progressively longer line whereby to be progressively effective to transmit energy to said vibratile element over different predetermined frequency ranges.

3. The invention set forth in claim 2 characterized in that each of said groups of pickup devices comprises a discrete pickup unit.

4. The invention set forth in claim 2 characterized in that said groups of pickup devices comprise unit devices, and characterized further in that certain of said groups have units in common with certain other groups.

5. The invention set forth in claim 2 characterized by the inclusion of acoustic means associated with said pickup devices for attenuating the acoustical energy of certain predetermined frequencies.

6. The invention set forth in claim 2 characterized by the addition of means interposed between each of said groups of pickup devices and said vibratile element for acoustically attenuating the energy supplied by said pickup devices to said element, the attenuating means of each of said groups being effective over a different frequency band.

7. The invention set forth in claim 2 characterized in that said groups of devices comprise unit devices, characterized further in that certain of said groups have units in common with certain other groups, and characterized still further in that each of said groups includes means for successively acoustically attenuating the energy transmitted to said element.

8. The invention set forth in claim 2 characterized in that said groups of devices comprise unit devices, characterized further in that each of said unit devices is provided with means for acoustically attenuating the energy transmitted thereby to said element, and characterized still further in that the attenuating means of all the units in any one group is effective at substantially the same frequency.

9. The invention set forth in claim 2 characterized in that said vibratile element comprises a diaphragm, and characterized further in that said pickup devices comprise a plurality of open-ended

tubes of progressively increasing lengths arranged in predetermined groups symmetrically with respect to the geometric center of said diaphragm.

10. The invention set forth in claim 2 characterized in that said vibratile element comprises a diaphragm, characterized further in that said pickup devices comprise a plurality of open-ended tubes of progressively increasing lengths arranged in predetermined groups symmetrically with respect to the geometric center of said diaphragm, and characterized still further in that said tubes all include means for acoustically attenuating the energy supplied thereby to said diaphragm, the attenuating means of the tubes of any one group all being effective at substantially the same frequency.

11. The invention set forth in claim 2 characterized in that said vibratile element comprises a diaphragm, characterized further in that said pickup devices comprise a plurality of open-ended tubes of progressively increasing lengths arranged in predetermined groups symmetrically with respect to the geometric center of said diaphragm, and characterized still further by the addition of a perforated disc in each of said tubes for acoustically attenuating the energy supplied thereby.

to said diaphragm, the discs of all the tubes in any one of said groups being effective at substantially the same frequency.

12. In a sound translating device, the combination of means for translating acoustical energy into electrical energy, said means including a vibratile element, a plurality of pickup devices displaced along a line and coupled to said element, said devices being adapted to actuate said element in accordance with the energy picked up thereby, and means for rendering said pickup devices progressively ineffective to actuate said element as a function of the frequency of the energy picked up thereby.

13. In a sound translating device, the combination of means for translating acoustical energy into electrical energy, said means including a vibratile element, a plurality of open-ended tubes of different lengths coupled to said element and constituting a line the length of which is determined by the length difference between the longest and shortest effectively operating tubes, and means for causing the effective length of said line to decrease with increasing frequency of acoustical energy picked up thereby.

FRANK MASSA.
